UNITED STATES PATENT OFFICE.

WILLIAM J. FITZGERALD AND ADDI BENJAMIN CADMAN, OF BELOIT, WISCONSIN.

MACHINE FOR WORKING CONCRETE OR THE LIKE.

Application filed August 18, 1919. Serial No. 318,181.

To all whom it may concern:

Be it known that we, WILLIAM J. FITZGERALD and ADDI BENJAMIN CADMAN, citizens of the United States, residing at Beloit, 5 in the county of Rock and State of Wisconsin, have invented certain new and useful Improvements in a Machine for Working Concrete or the like, of which the following is a specification.

10 Our invention relates to concrete working machinery and more specifically to machinery for laying concrete roads or pavements.

One of the objects of our invention is to 15 provide a machine for laying an entire pavement and simultaneously tamping and smoothing the surface of the cement by power.

One advantageous feature of our invention 20 is that the device is adapted to move along continuously over the pavement while tamping and smoothing the same whereby uniformity in the pavement is readily obtainable.

25 Another object of our invention is to provide means for quickly moving our entire machine along the road from place to place as it is needed.

A special object of our invention is to 30 provide a machine adapted to finish the surface of the cement with a crown, the machine being readily adjustable to lay a pavement of any desired slope or crown.

Further objects and advantages of our invention will become apparent as the description proceeds.

In the accompanying drawings Figure 1 is a plan view of a concrete pavement-working machine embodying the principles of 40 our invention. Fig. 2 is a front elevation and Fig. 3 is an end elevation of the same machine. Fig. 4 is a diagrammatic showing of the arrangement of the teeth on the drum. Figs. 5 and 6 are detail views 45 showing the attachment for the teeth of the drum. Fig. 7 is a plan view of a modified machine embodying adjustable means for producing a crowned pavement. Fig. 8 is a front elevation, and Fig. 9 an end 50 elevation of the same machine. Fig. 10 is

a detail view showing an end elevation of the connections for automatically raising and lowering the trailer flap. Fig. 11 is a detail showing these same parts separated from the rest of the machine. 55

Referring first to Figs. 1 to 6 inclusive, the device shown comprises a smoothing and tamping element, which in this instance is in the form of a drum or roller A, a carriage B supporting the drum A and adapted to move along tracks C, and means carried on the carriage for rotating the drum and for moving the carriage along the track. As shown in Figs. 1, 2 and 3, a rectangular frame is built up of channels 10 extending the entire length of the machine and end channels 11 underlying the side channels. Vertical channels 12 one at each end of the end channels 11 carry brackets 13 forming 60 bearings for axles 14 and 15, carrying wheel 16 resting on the tracks C. As shown in Fig. 2, these tracks C are laid parallel with the road bed on either side thereof outside the form 17, so as not to interfere with laying the pavement which extends uninterrupted 65 across the entire width of the street. Stakes 17^a may be used to hold the form 17 in place. 70

The drum A comprises a main shaft 18 extending between suitable bearings 19 and 20 attached to the end channels 11 and a plurality of diaphragms or spiders 21 suitably spaced along the length of the shaft. In the device shown, these spiders are octagonal and carry eight angle bars 22 (see 80 Fig. 3) each angle bar extending across and fastened to all of the spiders and carrying a plurality of teeth. As shown in Figs. 5 and 6, each of the teeth 23 comprises a suitable holder 24 preferably of metal, having a U-shaped face in which the main tooth block, preferably of wood, fits. The holder and tooth block are both clamped against the face of the angle bar 22 by a suitable bolt and restrained from turning by lugs 85 25 and 26 on the holder engaging the angle bar. 90

In Fig. 4 we have illustrated diagrammatically the arrangement of the teeth on the drum A. The teeth at each angle bar 22 100

are equidistantly spaced and on successive angle irons are arranged in overlapping relation as indicated by Fig. 4 which might be considered to show the marks that would 5 be made on a flat surface if the drum were rolled over it. It will be seen that the teeth *b*, *c*, *d* and *e* each overlap a trifle on the immediately preceding teeth *a*, *b*, *c* or *d* and that the angle iron carrying the teeth *e* 10 has a tooth exactly alined behind the first tooth *a*. With the drum carried slowly as a whole in the direction indicated by the arrow in Fig. 4 and the teeth moving in the same direction at a considerably higher 15 speed, it will be seen that the entire surface covered will be thoroughly tamped and smoothed by the wiping and pushing action of the teeth.

As clearly shown in Fig. 3 the front face 20 of each tooth is offset to lie in a plane passing on one side of the axis of the drum. As each tooth passes the vertical plane of the axle its front face extends up and slightly forward and pushes forward and slightly 25 downward on the concrete. This action will force enough concrete under the end of the tooth to generate a considerable pressure between the surface of the concrete and the end of the tooth.

30 Suitable means are provided for rotating the drum *A* and simultaneously moving the carriage slowly along the tracks. Herein we have shown a transmission adapted to take power from a suitable power unit mounted 35 on the base 27 and carrying a shaft 28 and fly wheels 29. The main transmission shaft 30 extending through the greater part of the length of the machine is driven from the engine shaft 28 by a suitable chain 31. The 40 drum *A* receives power from this transmission shaft 30 at one end through a suitable chain 32. The upper sprocket for this chain 32 may be disconnected from the main transmission shaft 30 by a suitable clutch 45 33 controlled by a lever 34 having the usual locking sector and connected with the clutch by a suitable connecting rod 35. For moving the carriage slowly while the roller *A* is working on the concrete, we have shown a 50 worm 36 and worm wheel 37 on an inclined shaft 38 at the left end of the machine, as seen in Figs. 1 and 2, driving a short countershaft 39 through suitable bevels 40. The countershaft 39 carries a sprocket adapted 55 to be connected to it by a suitable clutch 41 for driving the rear axle 15 of the carriage through a suitable chain 42.

When it is desired to move the machine 60 from one place to another the drum *A* is disconnected and also the worm transmission just described. We have provided means for driving the carriage rapidly along the tracks *C* in either direction comprising a pair of bevels 43 driving a short transverse 65 shaft 44 from the main transmission shaft

30. The bevel 45 on the end of this short shaft 44 rotates two bevels 46 on the countershaft 47 in opposite directions. A suitable clutch 48 is adapted to lock the countershaft 47 to either of these bevels, thus 70 driving the rear axle 15 through the chain 49 at a speed materially higher than that of the worm gear transmission at the other end of the machine. For the control of the low speed clutch 41 and the high speed clutch 75 48 we have provided a selective transmission from the control lever 50. As illustrated in Figs. 1, 10 and 11 connecting rods 51 and 52 to each of the clutches are pivotally connected to short arms 53 rotatable 80 around the same axis as the control lever 50 and carrying U-shaped fingers adapted to engage said control lever. Suitable spring elements 54 tend to hold the lever 50 in the 85 position shown in Fig. 1. The lever may be displaced forwardly to engage the slow speed arm 53 and then move down the slot 55 to engage the slow speed clutch. To operate the high speed clutch in either direction it is necessary to move the lever back 90 out of the slot 55 thus disengaging the slow speed clutch and rock it into engagement with the high speed fingers whereupon it can be moved in either direction in the slot 95 56 to operate the high speed clutch.

Referring to Figs. 10 and 11, a canvas flap 57 is adapted to be trailed along behind the machine to smooth the surface of the pavement behind the drum *A*. When the machine is moved from one place to another, 100 it is necessary to raise this flap. We have provided automatic means for doing this to eliminate the possibility of breaking or injuring the flap by careless operation. A plurality of bell crank levers 58 pivoted on the rear channel 10 have cords 59 at the ends of their horizontal arms extending down for suitable connection to the rocker arms 60 pivoted on the rear axle 15. These 105 rocker arms at their tips carry a nailing strip 61 to which the canvas flap is secured. One of the bell crank levers 58 is pivoted adjacent the slow speed arm 53 connected thereto by suitable bolt 62 (see Fig. 10) 110 sliding in a slot in said arm. A drag link 63 connects all the levers 58 together for simultaneous movement. Movement of the control lever 50 to engage the slow speed clutch will therefore rotate the bell crank levers 58 in counter clockwise direction as 115 seen in Fig. 11 and lower the canvas flap into operative position. Operation of the control lever to disconnect this clutch will move the levers 58 back into the position shown in Fig. 11 and raise the flap in which position it will remain while the lever 50 is 120 operated in the other slot 56 to move the machine from place to place.

In Figs. 7, 8 and 9 we have illustrated a 125 different embodiment of our invention com- 130

prising means for finishing the surface of the concrete with a crown or rise in the center of the pavement. Referring to this device, the tracks C' and carriage B' are substantially similar to those illustrated in Figs. 1, 2 and 3. The device carries two drums 64 and 65 similar to drum A each one extending from one end of the machine slightly past the center and each one receiving power at its outer end through a chain 66 driven from the main power shaft 67. The drum control lever 69 is connected to the clutches 68 for both the drums, and is adapted to connect or disconnect both drums simultaneously. The carriage control lever 70 and the means for controlling the motion of the carriage along the tracks C' are substantially identical with those shown in Figs. 1, 2 and 3 and need not be described again in detail.

The drum 64 is rotatably supported at its outer end in a bearing member 71 pivotally connected to a bracket 72 suitably mounted on the framework and at its inner end by a similar bearing 73 formed at the lower end of a vertically extending hanger rod 74. The hanger rod 74 extends up across the face of a short channel 75 and may be clamped thereto in vertically adjusted position by a suitable bolt 76 passing through a slot in the hanger rod. A diagonal brace 77 extends upwardly and rearwardly from the bearing 73 to take the thrust when the drum is spreading concrete. Another diagonal brace 78 at the outer end takes the thrust at this end relieving the bracket 72 of excessive stresses.

The second drum 65 is similarly mounted at the other end at the rear side of the frame being carried at its outer end by the bearing member 79 pivoted on the bracket 80 and braced by the brace 81 and at its inner end by the hanger rod 82 reinforced by the brace 83. A single short channel 84 supports the hanger rod 82 and receives the diagonal brace 77 from the other drum. It will be seen that the inner ends of the drums 64 and 65 may be adjusted vertically throughout a range sufficient to provide for making pavements having all the slopes customarily employed without throwing the driving sprockets at the outer ends of the drums out of alignment enough to interfere with the transmission of power to the drums.

It will be seen that we have provided a machine capable of rapidly smoothing off, tamping and finishing a pavement entirely by power and without the necessity of any workman going on the pavement while it is being worked. While we have shown and described in detail two illustrative embodiments of our invention, it is obvious that many modifications and variations will naturally occur to persons skilled in the art.

We aim in the subjoined claims to cover all

such legitimate variations and modifications.

We claim as our invention:

1. In a device of the class described, a spreading element having, in combination, a rotatable support and a plurality of outwardly projecting teeth carried by said support, each tooth offset axially from the preceding tooth by a distance less than the transverse dimension of the tooth. 70

2. In a device of the class described, a tooth comprising a wooden tooth block, a metal holder for said block, and a bolt extending transversely through the tooth block and holder to fasten said block and holder to each other and to a suitable support. 80

3. In a device of the class described, a tooth rotatable about a horizontal axis, a front face of said tooth slanting upwardly and forwardly in the direction of motion at the instant when the tip of said tooth passes the vertical plane extending through the axis of rotation. 85

4. In a device of the class described, a tooth comprising a tooth member proper and a holder therefor lying side by side, a bar adapted to support a plurality of teeth, and a single fastening means for fastening each tooth and its holder to said bar. 90

5. In a device of the class described, a rotatable support, a plurality of diaphragms carried by said support, a plurality of tooth carrying bars extending parallel to said support past said diaphragms, and a plurality of outwardly projecting teeth carried by each bar, said teeth being arranged in a plurality of helical series of such a pitch that each tooth partially overlaps and partially projects beyond the preceding tooth of the series. 100

6. In a device of the class described, a rotatable axle, diaphragms carried by said axle, angle irons extending parallel to said axle and attached to the peripheries of said diaphragms, each angle iron having one leg fastened to said diaphragms and the other leg extending outwardly, and a plurality of teeth mounted on the outwardly extending leg of each angle iron. 110

7. In a device of the class described, an angle iron, a tooth carried by one leg of said angle iron, said tooth comprising a U-shaped member abutting said leg and extending outwardly beyond the same, a filler having a tongue adapted to fit said U-shaped member, said U-shaped member and filler being detachably clamped to said leg. 115

8. In a device of the class described, a tooth comprising a tooth member proper, a tongue on one face of said member, a U-shaped holder adapted to receive said tongue, a bolt adapted to pass through said tooth member proper, said tongue and a support and lugs on said holder adapted to engage said support and hold said tooth rigidly in position. 125

- 24
9. In a device of the class described, a tooth comprising a tooth member proper and a holder therefor, and a single means for fastening said tooth member proper and holder to each other and to a suitable support.
10. In a device of the class described, a carriage adapted to extend from side to side of a street, tracks for said carriage, a rotatable drum mounted on said carriage and adapted to smooth and tamp the road-making material, means for rotating said drum, and means for moving said carriage along said tracks at a speed less than the peripheral speed of said drum.
11. The combination recited in claim 10 in combination with means for moving said carriage at a relatively high rate of speed in either direction.
12. The combination recited in claim 11 in combination with means permitting operation of said high speed means or of said low speed means, but not both.
13. In a device of the class described, in combination with a carriage, a smoothing and tamping element carried by said carriage, means for moving said carriage, and means dragged over the finished surface of the concrete by the motion of said carriage for wiping and smoothing said concrete, of other means for moving said carriage at a relatively high rate of speed in either direction, and automatic means for moving said smoothing and finishing means out of operative position before said high speed means can become operative.
14. In a device of the class described, a movable carriage, means for moving said carriage in one direction only at a slow speed, smoothing and tamping means carried by said carriage, means for moving said carriage in the opposite direction, additional smoothing means in the nature of an element dragging behind said carriage, and automatic means for raising said dragging element before said carriage may be moved in said last mentioned direction.
15. In a device of the class described, a plurality of rotatable smoothing and tamping elements mounted in overlapping relation, means for rotating said tamping elements and for moving them as a whole over the surface of the pavement, and means for varying the relative angular relationship of the axis of said elements.
16. In a device of the class described, two smoothing and tamping elements overlapping at their inner ends, means for moving said smoothing and tamping elements over the surface of the pavement, means for supporting the outer ends of said elements at a constant elevation, and means for adjusting the elevation of the inner end of each element.
17. A device of the class described having, in combination, a framework adapted to extend from side to side of a roadway, a rotatable tamping and smoothing means extending from end to end of said framework, tracks extending along either side of said roadway, wheels movably supporting said framework on said tracks, a power plant carried by said framework, transmission means from said power plant to said smoothing and tamping means and to said wheels, and control means for both said transmission means carried by said framework.
18. A device of the class described having, in combination, a framework adapted to extend from side to side of a roadway, rotating power driven elements carried by said framework for smoothing and tamping road making material, said elements extending inwardly from the outer ends of said framework into overlapping relation at the center, and adjustable means for raising and lowering the inner ends of said rotatable elements.
19. The combination recited in claim 18 in combination with bearings for the outer ends of said rotatable elements, said bearings being pivoted on horizontal pivots to permit adjustment of the inner ends of said elements.
20. The combination recited in claim 19 in combination with diagonal braces extending upwardly and rearwardly from said bearings to relieve said pivots of the thrust on said elements.
21. The combination recited in claim 18 in combination with upwardly and rearwardly extending braces at the inner ends of said elements adapted to receive the thrust exerted on said elements in operation.
22. The combination recited in claim 18 in combination with a single manually controlled means adapted to simultaneously connect or disconnect both of said rotatable elements with a source of power.
23. In a device of the class described, in combination, a framework, means for moving said framework in either direction at a relatively high speed or at a low speed in one direction only, an element adapted to drag behind said frame, means for raising and lowering said element out of and into dragging position, a selective transmission adapted to control the movement of said frame, and means connected with an element of said selective transmission for automatically lowering said dragging element when said frame is moved slowly and for automatically raising said dragging element when the transmission for moving said frame slowly is disconnected.
24. In a device of the class described, a front axle and a rear axle, means adapted to trail or drag behind said axles, said

means being pivotally mounted on said rear axle, a frame carried by said axles, selective means for driving said frame at different speeds, and means in the nature of a bell crank lever and a connecting cord for lowering said trailing means when said selective means is adjusted to move said carriage only in a given direction at a given speed.

In testimony whereof we have hereunto set our hands.

10

WILLIAM J. FITZGERALD.
ADDI BENJAMIN CADMAN.
